UNITED STATES PATENT OFFICE.

EUGENE ROBERTS BARBER, OF VALDOSTA, GEORGIA.

ATTACHMENT FOR CONVEYERS FOR BOTTLED SODA-WATER.

1,100,645.

Specification of Letters Patent. Patented June 16, 1914.

Original application filed July 31, 1912, Serial No. 712,510. Divided and this application filed October 10, 1913. Serial No. 794,416.

To all whom it may concern:

Be it known that I, EUGENE R. BARBER, a citizen of the United States, and a resident of Valdosta, in the county of Lowndes and 5 State of Georgia, have invented a new and Improved Attachment for Conveyers for Bottled Soda-Water, of which the following is a full, clear, and exact description.

The present application is a division of 10 an application filed by me July 31, 1912, Serial No. 712,510, and it relates particularly to a deflector attachment arranged in connection with a table forming part of the apparatus.

15 The invention will be particularly explained in the specific description following.

Reference is to be had to the accompanying drawings forming a part of this specification, in which similar characters of reference indicate corresponding parts in all the views.

Figure 1 is a side elevation of a machine showing one embodiment of my invention, parts being broken away; Fig. 2 is 20 a plan view; Fig. 3 is an elevation at right angles to Fig. 1, with parts in section, on about the line 3-3 of Fig. 2; and Fig. 4 is a fragmentary view on an enlarged scale showing a guiding and distributing attachment associated with the table, to prevent the bottles from being jammed.

In constructing the machine embodying 25 my invention, a suitable framework 10 is provided on which is mounted for rotation, a vertical shaft 11 carrying at its top a circular table 12, adjacent to which table and fixed to any convenient portion of the frame is a vertical guard rim 13, extending around the outside of the table 12, in close relation 30 thereto for nearly a complete circle, leaving an opening or throat 14, to which throat leads a conveyer belt 15. At the throat 14 and bridging the gap between the conveyer 15 and the table 12, is a horizontal rotary disk 16, pivoted at its center as at 17 on an upright stud 18, said disk overlapping both the table 12 and the conveyer belt 15, and adapted to be rotated frictionally by the movements of said belt and table.

35 Any suitable means may be provided for rotating the table and actuating the belt; in the example given the table is provided with peripheral rack teeth 19, meshing with which is a spur pinion 20 on a short vertical shaft 21, said shaft having a pulley 22. A

cross belt 23 extends around the pulley 22, and over a drive pulley 24 on a drive shaft 25, the various shafts being mounted in suitable bearings on the frame of the machine. The upper stretch of the conveyer belt 15 40 travels in the direction of the table 12 and runs over the bottom 26 of a runway, the vertical sides 27 of which guide the bottles one of which is indicated by dotted lines at 28, the bottles passing from the belt onto 45 the disk 16, and then to the table 12, as indicated at 28'. The belt 15 is of soft material, such as leather, fabric, or other non-metallic material, and at the end adjacent to the table 12, the belt passes over a broad 50 drive pulley 29, the lower stretch 15' of the belt passing beneath said pulley 29, and between the same and a pulley 30, the latter being mounted on a shaft 31 that has bearing blocks 32 supported on springs 33 that 55 tend to force the bearing blocks 32 upward to exert pressure on the lower run of the belt, causing the latter to be gripped between the upper and lower pulleys 29, 30 sufficiently tight to be driven. The pressure 60 on the belt may be regulated by screws 34 that take against the upper ends of the blocks 32. At the opposite end the belt runs over a pulley 35 mounted on an auxiliary frame 10^a that supports also the outer 65 end of the runway 26, 27. The driving shaft 25 of the pulley 29 and the shaft 31 of the pulley 30 are geared together by spur gears 36, 37, fixed on said shafts.

The rotation of the table 12 carries the 70 bottles away from the disk 16 as fast as they are received on the table, and, in order that the bottles may not become jammed on the table, nor jarred against each other, an attachment is provided whereby as the bottles 75 are carried around the table after having been received, they will be directed toward the center. Thus a horizontal arm 38 supported on the standard 39 from the frame 10 extends inwardly and overhangs above 80 the table 12, and on said arm are arranged depending blades, three of which are indicated in the example shown. The blades are designated by the numerals 40, 41 and 42, and the successive blades are separated by 85 an increasing distance toward the center, there being in practice, more than three employed. The arm 38 is supported sufficiently high above the table to permit the bottles 90 to pass therebeneath, and the depending 95

100 shaft 21, said shaft having a pulley 110 22. A

blades on said arm incline from the arm inwardly so as to deflect the bottles contacting therewith toward the central portion of the table. Thus the guard rim 13 prevents the 5 bottles from being carried outward beyond the edge of the table, and the blades 40, 41 and 42 prevent the bottles from jamming on the outside and cause them to move toward the center without violent contact with each 10 other.

In practice the feed of the bottles to the table is not greater than the attendants can handle, but the table has such a capacity that any temporary suspension in the work 15 of the attendants in removing the bottles from the table while the conveyer continues to operate and deliver bottles, will simply serve to collect the bottles on the table, first at the outside and then gradually adding 20 to the collected bottles until the table is filled.

Having thus described my invention, I claim as new, and desire to secure by Letters Patent:

25 1. The combination of a rotary table, means for feeding bottles thereto, and a series of deflectors supported above the table and at points between the outer edge and the

center of the table and tending to deflect the bottles in a direction inward from the outer 30 portion of the table.

2. The combination of a rotary table, means for feeding bottles thereto, and a series of deflectors supported above the table and at points between the outer edge and the 35 center of the table and tending to deflect the bottles in a direction inward from the outer portion of the table, the said deflectors being spaced apart and the distance between the outer deflectors being less than that of those 40 deflectors nearer the center of the table.

3. The combination of a rotary table, a rim surrounding said table for its major portion, means for delivering bottles to the table, and deflectors supported above the 45 table between the center and the rim and serving to deflect the bottles inwardly, there being a space at the center of the tables for assembled bottles.

In testimony whereof I have signed my 50 name to this specification in the presence of two subscribing witnesses.

EUGENE ROBERTS BARBER.
